ENGINE STARTING AID

Charles D. Snelling, Breinigsville, Pa.
Filed Jan. 17, 1962, Ser. No. 166,893
6 Claims. (Cl. 123—142.5)

This invention relates to a selective warm-up device for self-starting, engine-driven vehicles, and, in particular, to a warm-up device adapted to maintain the normal starting characteristics of an engine assembly under sub-freezing conditions which normally adversely affect the starting operation of heat engines of, for example, the internal combustion type.

The starting of engine-driven vehicles, such as automobiles, trucks, tanks, and the like, presents a problem in extremely cold climates, particularly in the arctic regions. Where such difficulties arise, it is not uncommon to resort to the well known expedient of warming up a cold selected portion of an engine assembly by the direct application of heat by, for example, a blow torch or similar direct-heating devices. In the case of the internal-combustion engine, the selected portion of the engine assembly to be heated might comprise the oil pan beneath the engine and/or the oil pan containing transmission fluid where an automatic transmission system is involved, the radiator, the carburetor, the fuel-injection line or other selected portions in which a fluid is involved, the performance of which is usually adversely affected by abnormal, sub-freezing conditions.

The use of direct-heating devices present the problem of localized over-heating and, unless a great deal of care is taken, damage of the part being heated is apt to occur. The use of other methods involving, for example, the transfer of heat by the convection flow of hot gases, such as by placing a heat source below the engine, have not proved to be too efficient, particularly in extremely cold environments.

I have found that I can overcome the disadvantages of prior methods by providing a method of bringing heat under controlled conditions directly to the selected part of the engine assembly to be heated by means of a direct application of heat at a portion of a heat-transfer system remote and separate from said selected part of the engine assembly. Thus, with my invention, I may, if I desire, use a blow torch as the heat source, but instead of applying the heat directly from the torch to the effected part, I apply heat directly to a heat-conductive element of a heat-transfer system, the location of direct-heat application being remote from the selected part to be heated, and I then conduct the heat under substantially controlled-temperature conditions direct to said selected part to be heated.

In one embodiment of my invention, I may, in applying heat to a conductive element remote from the engine, store some of said heat energy in a heat-storage device and call on the stored energy when it is needed to warm-up one or more selected parts of an engine assembly.

It is therefore an object of my invention to provide a selective warm-up device for use in combination with a self-starting engine powered by a hydrocarbon fluid and having selected portions including oil reservoir means, means for carbureting said hydrocarbon fluid, means for feeding said hydrocarbon fluid to said engine, fluid means for cooling said engine and the like, the performance of one or more of which may be adversely affected by agitating, sub-freezing environments.

Another object is to provide a selective warm-up device characterized by a heat-storage means capable of receiving and retaining heat for a given length of time and of controllably releasing it when desired for transfer to a

2

selected portion of a heat engine to be warmed up for starting purposes.

As a further object, I provide a method for controllably transferring heat to a selected portion of a heat engine by indirect means from a primary heat source.

These and other objects will more clearly appear from the disclosure and the accompanying drawings, wherein:

FIG. 1 depicts one embodiment of my invention utilizing a heat-storage means in combination with means for charging heat thereto in a controllable heat-transfer system for transmitting heat via heat exchangers to an oil-reservoir means of a heat-engine assembly;

FIG. 2 illustrates another embodiment of my invention in which a means is provided for receiving a concentrated application of heat for subsequent transfer under controlled-temperature conditions to a selected portion of a heat-engine assembly such as the oil pan;

FIG. 3 shows means by which the outside casing of a carburetor can be adapted for receiving an indirect application of heat; and

FIG. 4 depicts one embodiment of a heat-storage device chargeable electrically by means of heating elements connectable to a source of power supply, for example from an automobile battery.

Broadly stated, my invention provides in combination with a heat engine a selective warm-up device which includes means for developing a heat source, a first heat-exchanger means in heat-exchangeable relationship with said heat-developing source, at least a second heat-exchanger means in exchanging relationship with a least one selected portion of a heat-engine assembly desired to be warmed up, and heat-transfer means connectably associated with said heat-exchanging means at the heat source and with said heat-exchanger means at the selected portion of said heat-engine assembly. In a preferred embodiment, I may use control means associated with said heat-transfer means for connectably effecting heat transfer from said heat-source developing means to said selected portion of the heat-engine assembly.

In carrying out the broad method aspect of my invention, I apply heat directly to a heat-conductive element which has associated with it in heat-conductive relationship a reservoir, a substantial portion of which is preferably insulated from the environment. The reservoir forms part of a sealed system and contains a heat-exchanging fluid whereby said fluid is caused to evaporate over a range of temperatures. The method further includes conduct of the evaporated fluid to a selected portion of the engine to be warmed and maintaining it in heat-exchanging relationship with said selected portion, whereby the fluid gives up its heat to said portion and condenses; finally, the condensed fluid is returned to the reservoir for repeated heating. Where I use a blow torch for heating the heat-conductive element, I am not confronted by damage to any engine part, since no part of the engine would be touched by the torch.

As another preferred embodiment, I propose to use a heat-storage means in conjunction with the heat conductive element so that, during the heating thereof, I can store the heat for subsequent release to the heat-transfer system associated with the engine. In this connection, I refer to FIG. 1 which shows somewhat diagrammatically and partially in cross section a known heat-engine assembly indicated generally by the numeral 10 comprising a crank shaft 11 with main bearings 12 and connecting rod bearings 13. A camshaft 14 is shown provided with cams 14a and camshaft bearings 15. A piston 16 is depicted with connecting rod 17. An oil header 18 is diagrammatically indicated fed from oil reservoir 19 via oil strainer 20 and oil pump 21 through oil line 22. The oil header feeds oil as shown by the heavy lines branching

therefrom to main bearings 12, connecting-rod bearings 11, camshaft bearings 15, the bearings within the piston, and the like an oil pressure gauge 23 being also provided to indicate adequate oil feed.

Oil pan 24 is taken as illustrative of one of the selected portions of the heat engine assembly to be heated and is shown jacketed by heat exchanger 25 to provide space 26 for receiving heat exchange fluid from other portions of a heat-transfer system.

The system shown in FIG. 1 should not be taken as illustrating the proportion of the elements constituting the system, since it has been necessary to exaggerate the proportioning for purposes of clarity. The other parts of the system comprise heat-conductive element 27 formed of a block of heat-conductive metal, such as copper, having an exposed face adapted to receive the direct application of heat 28, as from a blow torch.

In this embodiment, element 27 is heat conductively associated with heat-storage device 29, which may also be of copper, having contained therein a fusible salt 29a capable of a relatively high heat of fusion. In heat-conducting relationship with container 29 is heat exchanger or evaporator 30 containing a heat-exchanger or thermodynamic fluid 31 properly chosen for its operating characteristics in the system, capable of boiling at a given temperature. The two containers are substantially insulated from the environment by insulation 32 of asbestos or other material. A heat-transfer line 33 is provided coupling the evaporator 30 with the oil pan at 34, a fluid return line 35 being provided leading from outlet 36 of the oil pan to inlet 37 of fluid storage reservoir 38. Where gravity feed-back of the condensed fluid is not possible, a pump 39 is provided to transfer the condensed fluid to storage reservoir 38 which is also preferably insulated by asbestos or other material 40. Insulation is also preferred for externally opposed parts of the pan 25 as well as the supply and return parts for the heat-exchanger fluid, but this has been omitted for clarity in all of the drawings.

A hand valve 41 may be employed for putting the circuit in operable condition having in series with it an additional control valve 42 operated by a temperature sensing element 43 to effect opening and closing of the valve depending on the temperature of oil reservoir 19.

It will be appreciated that the volume containing the heat-exchanger fluid, namely evaporator 30, oil-pan heat-exchanger 26, reservoir 38, and associated supply and return connections, is sealed. The choice of heat-exchanger fluid is dependent on a number of factors, including the following:

(1) It must be chemically stable and noncorrosive in the system throughout the anticipated range of temperatures.

(2) It should have as high a heat of vaporization as possible.

(3) It should boil in a pressure range that can be conveniently handled without resort to special techniques, for example, in the range extending between 15 in. Hg to 50 p.s.i.g.

(4) It should be characterized by relatively high vapor density.

With the foregoing system, I am enabled to store heat in container 29 while at the same time heating the fluid in container 30 by applying heat directly via a blow torch at 28 on the exposed face of element 27. After the blow torch is removed, the sensible and latent heat stored in the fused salt 29a continues to effect heating of the fluid in container 30 which evaporates, passes through line 33 into the oil pan heat exchanger at 34 where it gives up its heat to the oil, condenses and leaves the heat exchanger at 36 via pump 39 which delivers the condensed fluid to fluid reservoir 38 through inlet 37. With this method, overheating of the oil pan is avoided, while

at the same time warming up this portion of the engine assembly.

In a simple embodiment shown in FIG. 2, I may employ just a fluid heat-exchanger 45, suitably insulated by material 46 but in heat-conductive relationship with heat-conductive element 47 having an exposed face for receiving the direct application of heat 48. By applying heat to element 47, fluid 49 boils, evaporates and is conducted via heat-transfer tube 50 to heat exchanger 52 comprising a series connected length of tubing at the bottom of oil pan 53. As the fluid condenses and heats up the oil, it is adapted to return by gravity via line 54 to the bottom of container 45, as determined by the setting of a manual control valve 51. An advantage of this system is that it may be portable and used only when the occasion arises merely by connecting lines 50 and 54 to appropriate connecting points of the heat-exchanger associated with the oil pan. In this embodiment, the fluid may be water or other fluid of higher or lower so-called boiling point depending on the requirements.

While the invention has been described where the selected portion of the heat-engine assembly is the oil pan, it will be appreciated that other selected portions generally adversely affected by sub-freezing may also be similarly heated. Thus, I may warm the casing of the carburetor should it be necessary. Referring to FIG. 3, an outline of a carburetor casing 55 is indicated partially broken away at 56 at the reservoir side of the carburetor. The casing is shown surrounded by a heat-exchanger jacket 57 having an inlet 58 for receiving heat-exchanger fluid from a remotely situated evaporator of the type shown in FIGS. 1 and 2 and an outlet 59 from which the condensed fluid exits to be returned to a fluid reservoir or directly to the evaporator.

A similar arrangement may be used to warm up the radiator or other selected portion of the engine assembly, the performance of which is adversely affected by sub-freezing temperatures.

Instead of using the type of heating indicated for FIGS. 1 and 2, I may store up heat in the heat-storage portion of the system by the electrical application of heat. For example, the heat-storage system shown in FIG. 4 may be used comprising an electrical heating element 60 in heat-conductive relationship with heat-storage container 61, which in turn is in heat-conductive relationship with evaporator 62, the two containers being surrounded by insulator 63 of asbestos or other material to keep heat loss from the system down to a minimum. A thermostatic element 64 is provided in the region of the heat-storage bath in cooperative relationship with thermostat 65 for actuating said heating element when the temperature of the heat-storage device drops below a particular value. The heat-exchanger circulation line (not shown) connected to inlet 66 and exit 67 of the heating system may be provided with automatic valves actuated by a temperature-sensing device associated with a selected portion of the engine assembly to which heat is to be transferred. The power supply may be from an external electrical trickle charge or from the battery in the vehicle, or it may be the excess power generated while the engine is running. Thus, where a vehicle is being used intermittently in a cold climate, the heat-storage device could be charged while the vehicle is running so that when the vehicle is idle, the stored heat can be utilized to keep one or more portions of the engine assembly warm.

Examples of substances which may be used in the fused state as heat storage means are: sodium dibasic phosphate ($Na_2HPO_4 \cdot 12H_2O$) which melts at about $96.8^\circ F$. and solidifies to yield 120 B.t.u./lb. of salt; naphthalene ($C_{10}H_8$) which melts at $184^\circ F$. and has a heat of fusion of 64 B.t.u./lb.; cyanamide (H_2NCN) which melts at $109.4^\circ F$. and exhibits a heat of fusion of 89 B.t.u./lb. etc. Another substance is a material known commercially as Transit Heet 150 comprising trisodium

phosphate and water which melts between 150 and 155° F.

Examples of heat exchanging evaporator fluid include Freon 11 (CCl_3F) which boils at 75.3° F.¹ and has a heat of vaporization of about 78 B.t.u./lb.; Freon 113 ($CCl_2F-CClF_3$) which boils at 117.6° F. at a heat of vaporization of about 63 B.t.u./lb.; ethyl ether [$(C_2H_5)_2O$] which boils at 94.5° F.¹ and exhibits a heat of vaporization of about 150 B.t.u./lb.; acetone [$(CH_3)_2CO$] which boils at 133.5° F.¹ and has a heat of vaporization of about 225 B.t.u./lb.; etc.

Assuming that the selected portion of the heat assembly to be heated is the oil pan containing between 5 to 6 quarts of oil (weighing about 11 lbs.) and that its temperature is to be raised from about 0° F. to 60° F., the amount of B.t.u.'s necessary at an approximate specific heat of about 0.5 B.t.u. per lb. of oil would be in the neighborhood of about 330 B.t.u. Assuming a heat-storage unit containing about 8 lbs. of sodium dibasic phosphate heated to about 200° F. and an evaporator containing sufficient Freon 11 to maintain a continuous flow of fluid in the heat-transfer circuit and ignoring the super heat in the salt which is considerable, the heat of fusion (8×120 or 960 B.t.u.) should yield sufficient heat at 35% heat transfer efficiency (960×0.35 or 336 B.t.u.) to raise the temperature of the oil reservoir sufficiently to alleviate performance difficulties.

As stated hereinbefore, by having an automatic valve 42 shown in FIG. 1, the operation of which depends upon the temperature-sensing device 43, the amount of heat transferred can be controlled. For example, when valve 42 is off, the container 31 is emptied of its fluid in due course, after which heat transfer to the engine assembly virtually ceases. The heat conducting lines 33, 35 of FIG. 1 and 50, 54 of FIG. 2 should preferably be of non-conductive material so that heat loss to the environment is maintained at a minimum. Preferably, the lines should be insulated at least to the point of maintaining a substantial drop in heat loss from the system.

The heat-storage means may be adapted to get its heat charge from an exhaust-pipe heat exchanger, which is shown in FIG. 4a symbolized by the element 60 corresponding in function to that of FIG. 4. Thus, while the engine assembly is in operation, heat from the exhaust could be stored in the heat-storage means for eventual use in alleviating starting difficulties when the engine is cold. Various combinations of electrical and exhaust heating may also be employed.

In order to promote faster heat exchange between the heat-transfer fluid and the engine part to be warmed, heat-exchange fins may be utilized surrounding heat-transfer tubing immersed, for example, in the oil pan. As an alternative, the oil pan itself (e.g. 25 of FIG. 1) may be formed from a two-ply, roll-bonded sheet aluminum in which a maze of tubular pathways are provided between two aluminum sheets bonded together at predetermined areas, utilizing a resist material to prevent bonding at other predetermined areas defining a continuous pathway.

Although the present invention has been described in conjunction with preferred embodiments, it is to be understood that modifications and variations may be resorted to without departing from the spirit and scope of the invention, as those skilled in the art will readily understand. Such modifications and variations are considered to be within the purview and scope of the invention and appended claims.

What is claimed is:

1. In a heat-engine assembly powered by the combustion of a hydrocarbon fluid and having selected portions the performance of at least one of which during starting of the engine is adversely affected by a sub-freezing ambient temperature, the combination of a selective warm-

up device comprising means for receiving a direct application of heat, heat-storage means associated with said means for receiving direct application of heat, said heat-storage means having contained therein a heat-storage material characterized by a relatively high heat of fusion, a first heat-exchanger means in heat-exchanging relationship with said heat-storage means, a second means in heat-exchanging relationship with said at least one selected portion of said heat engine assembly which is adversely affected by said sub-freezing temperature, and heat-transfer means connectably associated with said first and second heat-exchanger means.

2. In a heat-engine assembly powered by the combustion of a hydrocarbon fluid and having selected portions the performance of at least one of which during starting of the engine is adversely affected by a sub-freezing ambient temperature, the combination of a selective warm-up device comprising means for receiving a direct application of heat, a fluid-confining heat-exchanger means in heat-exchanging relationship with said heat-receiving means, a heat exchanger condensing means in heat-exchanging relationship with said at least one selected portion of said heat-engine assembly which is adversely affected by said sub-freezing temperature, fluid-transfer means connectably associated with said fluid-confining heat-exchanger means and said heat-exchanging condensing means, and control means associated with said heat-transfer means for controlling heat transfer from said heat-receiving means to said at least one selected portion of said heat-engine assembly.

3. In a heat-engine assembly powered by the combustion of a hydrocarbon fluid and having selected portions the performance of at least one of which during starting of the engine is adversely affected by a sub-freezing ambient temperature, the combination of a selective warm-up device comprising heat-storage means adapted to receive a direct application of heat, an evaporator in heat-conductive relationship with said heat-storage means, a condenser in heat-exchanging relationship with said at least one selected portion of said heat-engine assembly which is adversely affected by said sub-freezing temperature, fluid-conducting heat-transfer means connectably associated with said evaporator and said condenser, and control means associated with said fluid-conducting means for effecting heat transfer from said evaporator to said selected portion of said heat-engine assembly.

4. The device of claim 3 wherein the control means comprises a temperature-sensing means associated with said at least one selected portion of said heat-engine assembly coupled to a valve associated with the fluid-conducting means and adapted to actuate said valve in accordance with the temperature sensed.

5. In a heat-engine assembly powered by the combustion of a hydrocarbon fluid and having selected portions the performance of at least one of which during starting of the engine is adversely affected by a sub-freezing ambient temperature, the combination of a selective warm-up device comprising a heat-storage means containing a fusible chemical capable of high heat content, said means being adapted to receive a direct application of heat, an evaporator in heat-conductive relationship with said heat-storage means, a condenser in heat-exchanging relationship with said at least one selected portion of said heat-engine assembly which is adversely affected by said sub-freezing temperature, a fluid-transfer tube coupling said evaporator to said condenser, a fluid-return tube from said condenser and connected via an off-on valve to said evaporator, and temperature-sensing means associated with said at least one selected portion of said engine assembly and coupled to said off-on valve for actuating said valve in accordance with the temperature at said selected portion.

6. In combination, a heat-engine assembly having a part adversely affected by sub-freezing ambient temperatures, a sealed thermodynamic system comprising an

¹ Boiling temperatures are handbook figures, for atmospheric pressure.

evaporator and a condenser, said condenser including a part in direct heat-exchanging relation with said engine part, said system further including a conduit connecting the upper part of said evaporator with said condenser and including a return-flow condensate conduit connected to the lower part of said condenser and for returning condensed heat-exchange fluid to said evaporator, heat-storage means in heat-conductive relationship with said evaporator, said heat-storage means including heat-exchanger means adapted to directly receive heat for transmission in the vapor phase to said engine part by way of said evaporator and said first conduit and said condenser.
